SUPERHEATER WITH BOILER

Roland S. Cooper, River Forest, Ill., assignor to
The Superheater Company, New York, N. Y.

Application February 18, 1933, Serial No. 657,396

6 Claims. (Cl. 122—478)

This invention relates to superheater boilers in which the superheater receives substantially all of its heat by convection from gases which have given up heat to water-cooled surfaces. It has 5 for its purpose the provision of an arrangement in which the degree of superheat obtained shall be more constant than heretofore, with variations in the load on the boiler.

In order to make clear the invention and how 10 it may be put into use, I shall describe it in connection with the drawing filed herewith which shows one illustrative application of the invention. In this drawing Figs. 1 and 2 are diagrammatic boiler-superheater arrangements given for 15 the purpose of discussing the theory of the invention, and Fig. 3 is a longitudinal section through a portion of a boiler embodying the invention.

Referring first to Fig. 1, there is shown here in 20 cross-section and rather diagrammatically a pair of spaced banks of water tubes 1 and 2. Between them is located a superheater 3. The gases for generating steam in the boiler and for superheating this steam are provided by a furnace 4 under the lower bank of water tubes. It will be 25 noted that in such an arrangement the gases give up some of their heat to the lower bank, thereby heating the water in the tubes of this bank and generating steam, before they strike 30 the superheater tubes. Both theoretical considerations and experience show that as the load on such a boiler goes up the superheat rises. One reason for this is that, at greater loads the gases striking the superheater are hotter than at lower 35 loads. A further reason, which has not been understood heretofore, is as follows. It usually happens that at the lower loads the gas velocity across some portions of the superheater is relatively low and only small amounts of gases flow 40 in contact with such portions. As the load rises, the velocity through these portions of the superheater becomes more nearly or even entirely equal to that of the gases across the other portions so that all of the portions are then worked 45 more completely. This condition is illustrated in Fig. 1 where the offtake 5 for the gases is shown as being at one side of the housing. With this disposition, the gases in the right-hand part of the pass have a higher velocity at low loads 50 than those in the left-hand part. The two parts may lie to the right and left of some line such as 6. To the left of this line the gases are relatively stagnant and the superheater elements lying in this zone pick up less heat per unit area 55 in a given time than those in the area to the right of the line. As the load on the boiler increases this line 6 will shift toward the left so that increasingly more tubes will be touched by gases flowing at the higher velocity until at the 60 maximum load all of the superheater surface will

be substantially equally effective. Thus the superheat will rise with the load. Just how much of the rise in superheat with a rise in the load is due to one of the two causes referred to above and how much to the other it is difficult to say. 5 My studies of the subject have convinced me that enough of it is due to the second cause to make the remedy suggested by me effective.

This remedy is brought out diagrammatically in Fig. 2. Here the general arrangement of boiler tubes, superheater tubes, furnace and offtake flue is just as it was in Fig. 1, but it will be noted that the distribution of the superheater surface in the space between the two banks of boiler tubes is different. This surface is so arranged 10 that the gases passing through those portions of the superheater nearest the right hand wall come in contact with more superheater surface than do those gases which pass through the space at points removed from the right-hand wall. The arrangement shows a gradually decreasing amount of superheater surface toward the left. The effect of this will be evident. As the boiler load rises, instead of as much additional superheating surface having its effectiveness increased 15 as was the case in Fig. 1 and as is the case with installations as hitherto made, a progressively decreasing amount is made more effective with such load increase. The increment in superheat 20 with rising loads is therefore not at the same rate as with the former arrangements but is at a decreasing rate. By properly grading the decrease in the amount of superheating surface the tendency 25 for the superheat to go up with the load is counteracted and a proper design according to 30 this invention will give constant temperature for 35 all loads.

It will be understood of course that the diagrammatic showing is merely illustrative. The 40 gas currents of the higher velocity at the lower loadings of the boiler are in the case shown in the two figures confined to the right portion of the space and this area expands toward the left with an increase in load. This is due to the fact that the outlet for the gases is at the right. In 45 general the engineer practicing my invention will determine in the first place through which portion of the space the higher velocity currents travel at low loads and through which spaces the velocity of the gases at the low loads is smaller. 50 He will then be in a position to design his superheater so that there is more superheating surface to be touched by the gases passing through the former portions of the space and decreasingly less in those spaces which progressively experience 55 an increase in their relative velocity.

Fig. 3 will illustrate this in a practical installation. A so-called interdeck superheater arrangement is here shown in a horizontal water tube boiler. The lower bank of boiler tubes 1a 60

connects the headers 7 and 8 while the tubes of the upper bank 2a connect the headers 9 and 10. Nipples 11—11 and 12 and circulators 13 connect the headers to each other and to the drum 14. Steam is taken off from the drum 14 by the steam pipe 15 and carried to the superheater inlet header 16 from which it flows through the superheater to the outlet header 17. The superheater elements 18 are placed between the two banks of tubes in the space between one set of nipples and the baffle 19. This is a common and well known arrangement. In the past the superheater surface was uniformly distributed between the baffle 19 and the nipples 11. In accordance with my invention, however, the superheater surface to be passed over by the hot gases decreases progressively from the baffle toward the nipples because it is my observation that at low loads the gases flowing through a space between the baffle 19 and some such line as indicated at 6a have a greater velocity than those flowing through the remaining part of the pass, and that with an increase in the load on the boiler the velocity of the gases equalizes more and more through the space to the right of the line 6a. It will be seen that by properly proportioning these relative amounts and the rate of decrease of the surface, the degree of superheat obtained may be held constant for varying loads.

30. It is possible that in boilers of the type shown in Fig. 3 the velocities of gas flow at low loads in a particular installation may for some reasons not be as assumed, but the greater velocities may occur in some other region, as for example adjacent to the right hand nipples 11 rather than to the baffles 19, these gases reaching the upper right hand corner of the setting and then following the roof toward the left to pass downward through the second pass. It will be clear that in that case the superheater surface will have to be arranged differently but that it will be equally possible to practice my invention. In any case, all that the designing engineer must determine is just where the high velocities occur at low loads and what space has gases of lower velocities at such low loads but has the flow sped up as the load on the boiler increases. He will then be ready to apply the principles of the invention to the installation in question.

50. I have chosen a horizontal water tube boiler in which to show my invention but it will be understood that I am not thereby confining myself to this type of boiler. It will be obvious that the invention has similar application to other boilers.

55. What I claim is:

1. A convection-heated superheater so arranged relatively to the gas flow over it that the gas stream effective in heating superheater surface increases in width as the steam flow through the superheat increases and that beginning at a steam and gas flow rate considerably below the intended maximum rate, the amount of superheater surface touched by the effective gases increases at a smaller rate than the width of the effective gas stream, whereby the rise of superheat temperature with increased output is reduced.
2. In a convection-heated superheater, a pass for hot gases wherein the velocity of gas flow in one part of the cross-section of the pass is greater

than in other parts, the proportion of said part of the total increasing with the load on the superheater, and a superheater arranged in said pass in such a way that with a certain load much below the maximum intended load on the superheater only a certain amount of the superheater surface is touched by the greater-velocity gases, and that this proportion increases with an increase of the load but at a rate lower than that of the increase in the proportion of the part of greater velocity gas flow, whereby the rise in superheat temperature with load is reduced.

3. In a boiler having a gas pass in which the width of the effective gas stream increases in width with the load on the boiler, a superheater arranged to raise the temperature of the steam from the boiler arranged in said pass, the amount of superheater surface touched by the effective gases increasing at a uniform rate for increases of load from a minimum up to a certain point and then increasing at a diminishing rate, said point being relatively far below maximum load.

4. In apparatus of the class described, a convection-heated superheater in a pass through which heating gases pass in such a manner that at one rate of total gas flow through the pass the velocity in one portion of the cross-section of the pass is greater than at the remaining portions and that the portion of relatively greater velocity increases as the rate of total gas flow increases, the superheater surface being so distributed through the pass that for equal increases of the portion of higher relative gas velocity diminishing increments of superheater surface touched by higher velocity gases are added, the difference in the rate at which the higher velocity gas area increases and the rate at which the superheater surface touched by higher velocity gases increases being such that the rate at which the final steam temperature varies with load variation is materially affected.

5. In a boiler having a gas pass wherein at low boiler loads the velocity of gas flow is greater in one part of the cross-section of the pass than in the other parts and wherein with a rise in the load the greater-gas-velocity part of the cross-section increases, a superheater in said pass with its surface so distributed that at low loads the greater-velocity gases touch a certain amount of the surface and that with an increase in load above an amount much below the intended maximum the amount of surface touched by the greater-velocity gases increases but at a slower rate than the part of the cross-section occupied by greater-velocity gases increases, whereby the rise in superheat temperature with load increase is reduced.

6. In a boiler, a gas pass through which the gas flow is such that through a portion adjacent to one side of the pass and increasing in size with the total gas flow the gas velocity is higher than outside of said portion, and a superheater whose surface is so distributed through said pass that for a certain distance inward from said side it increases uniformly with the distance from the side and beginning at a point spaced a substantial distance from the side opposite the surface increases at a diminishing rate, whereby the rate of rise of final steam temperature with increased gas and steam flow is lowered.

ROLAND S. COOPER.
